UNITED STATES PATENT OFFICE.

HARRY ROSE, OF UTICA, NEW YORK, ASSIGNOR TO REMINGTON AUTOMOBILE & MOTOR COMPANY, OF UTICA, NEW YORK.

CONTROLLING MECHANISM.

SPECIFICATION forming part of Letters Patent No. 705,302, dated July 22, 1902.

Application filed November 18, 1901. Serial No. 82,632. (No model.)

To all whom it may concern:

Be it known that I, HARRY ROSE, of Utica, in the county of Oneida and State of New York, have invented certain new and useful Improvements in Controlling Mechanism; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The object of my invention is to provide a controlling mechanism which is suitable and adapted for use with transforming-gears, such as are used in automobiles and similar vehicles.

For controlling transforming-gears a series of levers or other controlling means is required to produce the several speeds of forward motion in the vehicle, the back-up or reverse speed, and to apply the brake.

Figure 1 of the drawings shows a view, partially in perspective, of my controlling mechanism in which there are employed four foot-levers. Fig. 2 shows a side elevation of the same as seen from the left, as shown in Fig. 1. Fig. 3 is a vertical section showing one of the levers employed in the combination. Fig. 4 is a similar section showing another of the levers and other parts employed in the combination.

Referring to the reference letters and figures in a more particular description, 1 indicates a plate or base which is adapted to be inserted or inlet into the bottom 2 of a vehicle or automobile. The plate 1 is provided with a series of slots *a a*, &c., in which play the foot-levers 3 4 4 4. The levers 3 and 4 project above the plate 1 sufficiently to be conveniently operated by the toe and are pivoted on a shaft or bar 5 at their lower ends, which bar is supported in a set of downwardly-extending hangers 6, formed on the under side of plate 1. A spring 7 is attached at one end to the lever 3 and at the other to the bottom 2 of the vehicle and is adapted to move the lever 3 into its inoperative position. Similar springs 8 are provided for the other levers 4. Transversely of the slots *a a*

in the plate 1 and at the farther side of the plate there is supported a rock-shaft 9. This shaft is preferably mounted in supporting-bearings 10 on the under side of the plate 1. 55 The shaft 9 carries a catch 11 and a series of angular levers 12, all firmly secured to the rock-shaft. The rock-shaft is also provided with a spring 13, attached at one end to the shaft and at the other to the plate 1 or a fixed portion thereof and operating to throw the free or swinging ends of the catch 11 and levers 12 upward. The lever 3 is provided with a pin or projection 14, adapted to engage with the hook or catch 11. The ends 65 of the several levers 12 are arranged to lie close to the side of the levers 4, and each lever 4 is provided with a projecting pin 15, adapted to engage with its lever 12.

16 indicates a connecting-rod extending to 70 the mechanism to be operated by this lever, while 17 indicates the several connecting-rods of the levers 4 4, which connect them with the mechanism to be severally operated thereby.

For the purpose of more clearly describing 75 the device I will say that the connecting-rod 16 is attached to the mechanism which controls the fast speed of the vehicle, while the connecting-rod 17 of the next adjacent lever controls the slow speed, that the next lever 80 controls the vehicle-brake, while the farther lever controls the reversed speed.

When all the connected mechanism is out of operation, the levers 4 4 will stand in the positions shown in full lines in Fig. 1 and the 85 lever 3 will stand in the position shown by dotted outlines in this figure. The operator may bring into use the mechanism under control of any of the levers 4 by forcing them to or toward the position shown in dotted outlines in Fig. 1. When any of them are relieved, they will be returned to their inoperative positions by the springs severally controlling them. The operator may also force the lever 3 from the position shown in dotted 90 outline in Fig. 1 into that shown in full lines in the same figure, where it is caught and held by the catch 11 engaging with the pin 14 therein. When any of the levers 4 are operated while the lever 3 is held by the catch, as 100 stated, the projection or pin 15 of the said lever 4 rides on the inclined or angular portion

of the lever 12 at once upon being started from its inoperative position, causing the shaft 9 to rock and throw out the catch 11, allowing the lever 3 to be thrown out of operation by the spring 7. The arrangement and connections of the levers 4 4 and the mechanism are such that the mechanism is really not thrown into operation until the levers reach their limit of throw or substantially so.

10 It will thus be seen that the mechanism controlled by this controlling device is free from injury by throwing in two or more speeds at once or applying the brake while the high-speed mechanism is in use.

15 While it has been stated that the lever 3 controls the fast speed of the vehicle, it is obvious that this is not necessarily so; but the lever 3 can be made to control the slow speed or any intermediate speed. It is preferably 20 connected to the speed which will be most in use, as the catch securing the lever relieves the operator from maintaining constant pressure thereon.

25 It is evident that the mechanism described may be modified in several particulars without departing from the spirit of my invention.

What I claim as new, and desire to secure by Letters Patent, is—

30 1. The combination in a controlling mechanism of an operative controlling-lever, a spring for returning said lever to its inoperative position, a catch for securing said lever in operative position, a second adjacent controlling-lever, a spring for returning said second lever to its inoperative position and means coöperating with said second lever for releasing said catch, substantially as set forth.

2. The combination in a controlling mechanism of a set of controlling-levers operating in parallel planes and arranged adjacent to each other, a catch for securing one of said levers in operative position, means for coöperating with each of the other levers of the set for releasing said catch upon operating any of said other levers and springs for returning said several levers to their inoperative positions, substantially as set forth.

3. The combination in a controlling mechanism of a swinging lever, means for returning it to its inoperative position, a catch for securing it in its operative position, a second adjacent controlling-lever and means coöperating with said second adjacent controlling lever for throwing out or disengaging said catch, substantially as set forth.

4. In a controlling mechanism, the combination of the base or plate, a series of controlling-levers pivotally supported beneath said base or plate and operating through slotted openings therein, means for returning each of said levers to their inoperative positions, a catch 11 for securing one of said levers in operative position, a rock-shaft on 65 which said catch is mounted, angular levers 12 secured to said rock-shaft and means on the several other levers of said set for engaging with, or operating on said levers 12 whereby the catch is released, substantially 70 as set forth.

In witness whereof I have affixed my signature, in presence of two witnesses, this 12th day of October, 1901.

HARRY ROSE.
